UNITED STATES PATENT OFFICE.

STARLEY F. BEASLEY, OF KANSAS CITY, MISSOURI, ASSIGNOR OF ONE-HALF TO
FRANK E. WELLMAN, OF KANSAS CITY, KANSAS.

TRUCK-BOLSTER REINFORCEMENT SADDLE.

Application filed December 31, 1926. Serial No. 158,224.

This invention relates to truck bolsters for railway cars and more especially to reenforcement saddles for pressed steel or built-up bolsters, which after a period of years 5 have a tendency to crack and become deformed at the center. My object is to provide a saddle which is susceptible of application to new bolsters but is primarily designed for use on old bolsters where they 10 become weakened by cracking, a saddle of the type contemplated being readily and economically applied with proper facilities and restoring the bolster to its original or even greater strength. 15 With the general object named in view the invention consists in certain new and useful organizations of parts as hereinafter described and claimed; and in order that it may be fully understood reference is to be 20 had to the accompanying drawing, in which:—

Figure 1 is a sectional perspective view of a built-up bolster equipped with a saddle embodying the invention.

Figure 2 is a cross section of the construction shown in Figure 1.

Figure 3 is a side view of the construction shown in Figure 1.

Figure 4 is a detail perspective view of 30 the saddle.

In the said drawing, where like reference characters identify corresponding parts in all of the figures, the bolster shown is of hollow type, being composed of a lower 35 channeled or U-shaped member 1 and an upper channeled or U-shaped member 2 superimposed in inverted position upon the lower member 1, the latter being provided with laterally projecting external flanges 3, and 40 the member 2 with corresponding flanges 4 riveted or otherwise secured together.

As customarily made angle flanges (not shown) are riveted to the upper corners of the upper or top member 2 and project laterally therefrom, and a centering plate of the type hereinafter described rests floating upon the top member at its center and is riveted at opposite sides to the laterally projecting flanges mentioned. After a period 45 of more or less extended service, bolsters of the type described are susceptible to crack-

ing at or near their center portion and the method heretofore used of making a repair has been to bend plates to fit on the bolster and to rivet them thereto. This method does 55 not make the most efficient or dependable repair and furthermore is not economical.

I have, therefore, devised a saddle which can be readily and economically applied to the bolster and provide a support for the 60 center plate, but before the saddle can be secured in position the center plate and the angle flanges mentioned must be removed.

The saddle 5 is of channeled form and of size to fit over the central portion of the 65 bolster and rest upon the top and fit snugly against the sides thereof, the arms of the saddle resting upon the flanges 4. The saddle is provided at its upper corners with outwardly projecting flanges 6 and the arms of 70 the saddle are provided near their lower edges with notches or recesses 7 to accommodate the conventional brake beam adjuster bar, not shown.

The top of the saddle is provided at its 75 ends with holes 8 for the reception of rivets 9 by which it may be firmly secured to the top member of the bolster, and the sides of the saddle are provided with holes 10 for the reception of rivets 11 securing said sides to 80 the sides of the top member of the bolster. The outwardly projecting flanges 6 are provided with a series of holes 12 for the reception of rivets 13 by which the center plate 14, superimposed upon the saddle, is 85 secured firmly thereto, the saddle having the customary central socket 15 in its upper side.

From the above description it will be apparent that I have produced a construction 90 embodying the features of advantage set out as desirable, and while I have described and claimed the preferred embodiment of the invention, it is to be understood that I reserve the right to make all changes properly falling within the spirit and scope of the 95 appended claims.

I claim:—

1. The combination with a built-up bolster, of a saddle engaging the top and sides of the bolster and riveted to the latter, and 100 a center plate superimposed on the central part of and riveted to the saddle; the lower

edges of the sides of the saddle having adjuster-bar receiving recesses.

2. The combination with a built-up hollow bolster composed of superimposed relatively-inverted channel members provided with external engaging marginal flanges secured together, of a saddle secured to and embracing the top and sides of the upper

bolster member and fitting at its lower edges upon the said external flanges, and a center ¹⁰ plate superimposed on the central part of and riveted to the saddle.

In witness whereof I hereunto affix my signature.

STARLEY F. BEASLEY.
